UNITED STATES PATENT OFFICE.

MOGENS CHRISTIAN CHRISTENSEN, OF TACOMA, WASHINGTON, ASSIGNOR OF ONE-HALF TO RANDOLPH F. RADEBAUGH, OF TACOMA, WASHINGTON.

GATE-VALVE.

1,398,678.

Specification of Letters Patent. Patented Nov. 29, 1921.

Application filed May 5, 1920. Serial No. 379,091.

To all whom it may concern:

Be it known that I, MOGENS CHRISTIAN CHRISTENSEN, a citizen of the United States, residing at Tacoma, in the county of Pierce 5 and State of Washington, have invented new and useful Improvements in Gate-Valves, of which the following is a specification.

This invention relates to valves used for drawing off the contents of molasses barrels 10 and the like, and has for its object the provision of a gate valve provided with automatic locking means which will operate to lock the valve in closed position so that accidental opening thereof will be prevented.

15 In valves of this type there is a projection serving as a handle for effecting opening and closing and it very frequently occurs that the clothing of a person passing catches on this projection and causes the valve to be 20 opened with resultant waste. It is with this objection in mind that the present invention has been designed.

An important object is the provision of a device of this character in which the locking means is so constructed that it will snap into place the instant that the valve is closed but yet which may be very quickly and easily released when it is desired to open the valve.

30 An additional object is the provision of a device of this character which will be simple and inexpensive in manufacture, highly efficient in use, durable in service, and a general improvement in the art.

35 With the above and other objects and advantages in view, the invention consists in the details of construction to be hereinafter more fully described and claimed and illustrated in the accompanying drawings in which—

40 Figure 1 is a side elevation of the valve,
Fig. 2 is a front elevation,

Fig. 3 is a sectional view on the line 3—3 of Fig. 1 with the valve in closed position, and

45 Fig. 4 is a similar view with the valve in open position.

Referring more particularly to the drawings, the numeral 10 designates the body of the valve which is of a well known type. 50 This body is of the usual shape and has one end threaded for engagement within a barrel or cask and has its other end provided with an arcuate bearing face or plate 11. The movable part of the valve comprises a 55 U-shaped yoke 12 having its arms straddling

and pivoted upon the body 10, as shown at 13. At its right portion this yoke carries a socket 14 within which is disposed a coil spring 15 which engages against a plate 16 the outer face of which is curved on the same 60 arc as plate 11 against which it fits tightly for forming a closure for the bore of the body 10. Also formed on this yoke is a handle 17 by means of which the valve may be opened and closed. It is observed that 65 in order to open the valve it is merely necessary to grasp the handle 17 and swing the yoke so as to uncover the hole in the body. These parts are all well known and I claim 70 no novelty for them but show them as being necessary to a full understanding of the invention.

In carrying out my invention I provide a leaf-spring 18 secured upon one arm of the yoke 12 and extending through a guide 75 bracket 19 carried by said yoke arm. The other end of this spring projects beyond the edge of the arm of the yoke and has secured thereto a block-like member 20 having a finger piece or handle 21 formed thereon and 80 carrying a pin 22 which is adapted to ride over an inclined shoulder 23 on that side of the discharge end of the body. I also provide a recess 24 in the side of the body within which the pin 22 engages when the 85 valve is in closed position. The valve being closed, when it is desired to open it, it is merely necessary that the operator only grasp the handle 17, place his thumb upon the finger piece or handle 21 and press the 90 same laterally against the force of the spring 18 to disengage the pin 22 from the recess 24. The yoke is now unlocked and may be opened in the ordinary manner.

From the foregoing description and a 95 study of the drawings it will be apparent that I have thus provided a highly efficient and yet simply constructed locking device by means of which a gate valve may be locked close to prevent it from accidentally 100 opening. It will also be observed that the locking device does not necessitate any alterations in the conventional gate valve and that it may therefore be applied easily to existing gate valves of the well known 105 type.

While I have shown and described the preferred embodiment of my invention, it is of course to be understood that I reserve the right to make such changes in the form, con- 110

struction, and arrangement of parts as will not depart from the spirit of the invention or the scope of the subjoined claims.

Having thus described my invention, I 5 claim:

1. In combination with a gate valve structure including a body and a movable yoke pivoted thereto and carrying a closure plate for the discharge end thereof, a locking device comprising a spring secured at one end upon the yoke, a guide bracket carried by the yoke and through which said spring extends, a block member carried by the projecting end of the spring and formed with 10 a handle, and a catch projecting from said block member, the body being provided with a recess for the reception of said catch and having an inclined shoulder leading thereto.
2. In combination with a gate valve structure, including body or spout member and a movable yoke pivoted thereto and carrying a plate serving as a closure for the discharge end of the spout, a locking device comprising a spring secured at one end to 15 the yoke and provided with a finger piece or handle, and a lateral projection carried by the spring, said body or spout having a recess for the reception of the said lateral projection.
3. In combination with a gate valve structure, including a bored body member and a yoke member comprising side arms pivotally secured to the opposite sides of said body member and a plate connecting the outer 20 ends of said arms and serving as a closure

for the discharge end of said body member, and a spring actuated latch carried by one of said yoke arms and laterally engaging the body member to lock the closure plate against the discharge end of the said body 40 member.

4. In combination with a gate valve structure, including body member and spout carried thereby, the discharge end of said spout having an arcuate face and a yoke 45 member comprising a pair of side arms pivotally secured at one end to the body member, and an arcuate closure plate carried at the other end of said arms, an inclined shoulder mounted on the body member, a 50 plate spring secured at one end to one of the side arms and carrying a finger piece at its free end, a lateral projection extending inwardly from said spring and adapted to engage and ride upon said inclined shoulder, 55 said body portion having a recess for the reception of said lateral projection, whereby to maintain the closure plate in locked position.

5. In combination with a gate valve structure, including a body member or spout and a member comprising side arms and a closure plate, said side arms extending therefrom and pivotally secured to the body member, and a laterally impelled movable locking means carried by one of said side arms and operating automatically to lock the yoke against movement when the closure plate is 60 in closed position.

MOGENS CHRISTIAN CHRISTENSEN.
